UNITED STATES PATENT OFFICE.

WILLIAM B. POTTER, OF SCHENECTADY, NEW YORK, ASSIGNOR TO THE
GENERAL ELECTRIC COMPANY, A CORPORATION OF NEW YORK.

MOTOR-CONTROLLER.

SPECIFICATION forming part of Letters Patent No. 726,987, dated May 5, 1903.

Application filed August 2, 1899. Serial No. 725,852. (No model.)

To all whom it may concern:

Be it known that I, WILLIAM B. POTTER, a citizen of the United States, residing at Schenectady, county of Schenectady, State of New York, have invented certain new and useful Improvements in Motor-Controllers, of which the following is a specification.

This invention relates to devices for controlling the application of power to motors. It is especially designed for railway service in connection with electric motors where the rapid operation of the circuit-controller in admitting current to the motor endangers the safety of the apparatus, is extravagant in the use of current, or causes jerky or unduly rapid acceleration.

The object of the invention is to provide a governing device positively preventing the too-rapid operation of the controller, or, in other words, a device which will force the operator or motorman to admit current slowly through the controller by positively locking the controller against motion if the handle be turned too rapidly, but which will always permit a rapid unobstructed movement between definite periods.

In carrying out the invention I place in operative relation to the hand-operating device a locking-detent elastically connected to a moving part and serving to insure a definite time interval or period of rest between controller steps without interfering with the proper operation of the controller in passing from one step to another. In car-controllers as commonly constructed the power-cylinder turned by the motorman's handle when the motors are being connected into circuit is provided with a star-wheel the undulating teeth of which are engaged by a spring-actuated pawl shod with a roller. By its effect on the teeth of the star-wheel this pawl causes the controller-cylinder to move suddenly from one position to another, thereby insuring a sudden rupture of the circuits at the controller-contacts as the controller is moved from one position to another, as well as determining the position of rest at each step of the controller. I mount an auxiliary ratchet-wheel having a series of teeth on the same

axis as the star-wheel, and I connect to the pawl above mentioned an auxiliary pawl or detent movable with and controlled by the main pawl, but having a certain amount of free motion with relation thereto and capable of being impelled by its moment of inertia when the main pawl rides too rapidly over the inclines of the star-wheel into engagement with the teeth of the ratchet-wheel, thus arresting the movement of the motorman's controlling - handle and positively preventing a too-rapid movement of said controller through a series of steps. A "time-limit" retracting device for withdrawing the auxiliary pawl or detent from engagement with the ratchet-wheel may also be provided, and by adjusting this device the rate of enforced slow movement of the controller may be varied.

My invention, although as specifically embodied in the drawings of this application shown applied to a controller for electric motors, is in its main features of general application and capable of use with other modes of transmitting power from a source to a motor driven by said power.

The invention in its broader aspect comprises a motor-controller capable of rapid and unobstructed movement between definite stages, but enforcing a slow movement through a series of such stages.

It comprises also a controller provided with a variable time-limit device for adjusting the speed of application of power to the motor.

It comprises, further, means for enforcing a slow and gradual application of power by the movement of a detent brought into engagement with a movable part of the controlling device by the force of inertia under rapid movement and means for varying its moment of inertia.

It comprises, further, other more specific features, which will be hereinafter more fully described and will be definitely indicated in the claims.

In the drawings which illustrate one form of the invention, Figure 1 is a top plan view, with part of the cover broken away, of an electric-motor controller. Fig. 2 is an en-

larged detail view of the device which limits the speed of application of power to the motor, showing also some modifications in the details of construction. Fig. 3 shows a second modification of the speed-limiting device.

1 represents a star-wheel fast to the power-cylinder of a motor-controller, the squared end of the shaft of which is indicated at 2 and upon which is applied a handle manipulated by the motorman. 3 represents the shaft of a similar current-reversing cylinder. The several teeth of the star-wheel correspond to the steps or positions of the controller, and in the particular controller indicated in the drawings these steps operate to gradually cut out resistance and couple two or more motors from a condition of open circuit to a parallel relation to the supply-circuit. The teeth of the star-wheel are engaged by a roller mounted on the end of a spring-retracted pawl 4, which follows the undulations in the periphery of the star-wheel. With this organization, which is substantially that commonly provided in car-controllers, it is possible for the motorman to turn his controller rapidly from a state of open circuit to the final condition of adjustment of the motor-circuits, thereby giving an insufficient time for the motors to start up and endangering their safety by reason of the great rush of current, as well as subjecting the passengers to inconvenience and danger and all parts of the car to excessive strains by reason of sudden jumps in acceleration. I provide a positive check against such a sudden operation of the controllers by employing an auxiliary pawl or detent 5, which may be pivoted on the same axis as the pawl 4 and is connected to it by means of an elastic connection or tension device, such as a spring 6, the strength of which may be varied by an adjusting-nut, as indicated. The tip of this pawl coöperates with a ratchet-wheel 7, mounted on the power-cylinder, and is so arranged relatively to the tip of the pawl 5 and the indentations of the star-wheel that its notches will be in position to receive the pawl when the roller on the main pawl rests in a depression of the star-wheel. The pawl 5 is provided with an adjustable weight 8, which may be shifted along a post and locked by a set-screw, so as to alter the moment of inertia of the pawl about its pivot. It is provided also with a retarding device by which its rapidity of retraction after engaging a tooth of the star-wheel may be varied. The spring 6 is capable of acting as a variable retractile force under the influence of the regulable adjusting-screw; but a more protracted time limit may be insured by providing, as shown in the drawings, a dash-pot 9, into which works a plunger pivoted to the pawl. With this organization a rapid movement of the controller-handle by the motorman permits the roller-shod pawl engaging the star-wheel to drop quickly into one of the depres-

sions of the star-wheel, thereby communicating a considerable impulse to the pawl 5, which is free to obey the impulse, and distends the spring 6 and moyes the plunger of the dash-pot, air entering through a leak-opening in the plunger or wall of the dash-pot, as indicated in the drawings. On the next forward movement when the roller drops into the adjacent tooth of the star-wheel the pawl will be in position to engage one of the teeth of the ratchet-wheel, thereby locking the controller against further movement until under the retractile force of the spring 6 it is automatically unlocked, when the detent is drawn out of engagement with the tooth. The rate of operation of this spring constituting the automatic unlocking device, and therefore the time during which the controller is locked, depends upon the moment of inertia of the pawl or detent, the speed of leakage of the air trapped in the dash-pot, and the tension of the retracting-spring.

The sensitiveness of operation may be increased by providing the dash-pot with an inwardly-opening valve, permitting a rapid introduction of air upon forward movement of the plunger, but leaving only a small opening on its rearward movement. This type of construction is shown in Fig. 2, where a spring - actuated inwardly - opening check-valve 10 is provided, permitting a comparatively free admission of air to the cylinder on forward movement of the plunger, but leaving only a small opening for the exit of air upon its backward movement. It is not absolutely necessary to provide the dash-pot, although such a device or its equivalent affords a convenient means of varying the length of time during which the arrest of the controller is effected.

With the construction above described it will be evident that whenever the controller is operated slowly its movement will be entirely unobstructed as far as the locking device is concerned and, further, that it may be operated as rapidly as desired between steps, but that the movement of the controller through a series of steps must necessarily be sufficiently slow to permit the motor or motors to gradually accelerate in speed.

In Fig. 3 is shown an organization in which the dash-pot is dispensed with. In this case the spring 6 brings the locking pawl or detent normally into engagement with a lug or stop 11, mounted on the roller-shod pawl. When the controller is operated too rapidly, the speed of the roller-shod pawl toward the depressions in the star-wheel is imparted to the locking-pawl, and when the main pawl is arrested by the bottom of the groove of the star-wheel the inertia of the locking-pawl carries it forward against the tension of the spring 6 into engagement with a tooth of the ratchet-wheel, thereby arresting the movement of the controller-handle. It will be

withdrawn with more or less quickness, according to the tension of the spring 6, the momentum of the pawl, and its frictional engagement with the tooth of the ratchet-wheel, the latter varying with the shape of the nose of the pawl and the inclination of the tooth.

It will thus be seen that with the apparatus herein described the controller can be adjusted for operation at any desired speed 10 by shifting the adjusting-weight 8 and altering the tension of the spring 6, thereby predetermining the rapidity with which the motor-man can cut into circuit the motors. It will be seen also that the length of time during 15 which his movement can be arrested in case he applies the power too quickly can be definitely predetermined and adjusted by a change of the rate of leakage in the dash-pot or a change of the controlling devices of the 20 locking-pawl so as to alter its sensitiveness.

By my construction the controller may be operated rapidly without obstruction between the steps or operative positions of the controller, thus preventing damaging arcing at 25 the contacts by permitting a quick rupture, while the slow step-by-step movement necessary in order that the motors may gradually accelerate in speed is positively enforced.

What I claim as new, and desire to secure 30 by Letters Patent of the United States, is—

1. In combination, an electric controller having a series of operative positions or steps, means for causing a sudden movement of the movable member of the controller as it is moved from step to step, and means for positively preventing a rapid movement of said member through a series of steps.

2. In combination, a controller having a series of operative positions or steps, and a governing device constructed and arranged to permit a rapid unobstructed movement between steps and to limit the speed of movement through a series of steps.

3. In combination, a controller, and a governing device elastically connected to a moving part and operating by reason of its inertia to positively lock the controller against too rapid a movement.

4. In combination, a controller having a series of operative positions or steps, and a governing device elastically connected to a moving part and operating by reason of its inertia to positively lock the controller against too rapid a movement through a series of steps.

5. In combination, a controller, a governing device operating automatically upon too rapid a movement of the controller to positively lock the said controller against movement, and a "time-limit" device for unlocking said governing device.

6. In combination, a controller, a speed-controlled device for locking said controller against movement, and a "time-limit" device for unlocking said controller.

7. In combination, a controller, a speed- 65 controlled device for locking said controller against movement, and automatic means for unlocking said controller.

8. In combination, a controller, a speed-controlled device for locking said controller 70 against movement, automatic means for unlocking said controller, and means for determining the rate of operation of said automatic means.

9. In combination, a controller, a speed- 75 controlled device for locking said controller against movement, automatic means for unlocking said controller, and means for varying the rate of operation of said automatic 80 means.

10. In combination, a controller, a speed-controlled device for locking said controller against movement, automatic means for unlocking said controller, and a dash-pot for retarding the operation of said automatic 85 means.

11. In combination, a controller, a device operating by reason of its moment of inertia to lock said controller against movement, and automatic means for withdrawing said device, 90 so as to permit further movement.

12. In combination, a controller, a device operating by reason of its moment of inertia to lock said controller against movement, automatic means for withdrawing said device, 95 and means for varying the moment of inertia of said device.

13. In combination, a controller, a device operating by reason of its moment of inertia to lock said controller against movement, automatic means for withdrawing said device, 100 and means for varying the rate of operation of said automatic means.

14. In combination, a controller, a device operating by reason of its moment of inertia 105 to lock said controller against movement, automatic means for withdrawing said device, and means for determining the rate of operation of said automatic means.

15. In combination, a controller, a device 110 operating by reason of its moment of inertia to lock said controller against movement, and a spring for withdrawing said device, so as to permit further movement.

16. In combination, a controller, a device 115 operating by reason of its moment of inertia to lock said controller against movement, a spring for withdrawing said device, and means for varying the moment of inertia of said device. 120

17. In combination, a controller, a device operating by reason of its moment of inertia to lock said controller against movement, a spring for withdrawing said device, and means for varying the tension of said spring. 125

18. In combination, a controller, a device operating by reason of its moment of inertia to lock said controller against movement, a

- spring for withdrawing said device, and means for determining the rate at which said device is withdrawn.
19. In combination, a controller, a device operating by reason of its moment of inertia to lock said controller against movement, a spring for withdrawing said device, and means for controlling the operation of said spring.
20. In combination, a controller, a device operating by reason of its moment of inertia to lock said controller against movement, a spring for withdrawing said device, and a dash-pot for controlling the operation of said spring.
21. In combination, a controller, a star-wheel mounted on said controller, a spring-actuated pawl engaging said star-wheel, a detent elastically connected to said pawl, and a series of teeth on the controller in position to be engaged by said detent.
22. In combination, a controller, a star-wheel mounted on said controller, a spring-actuated pawl engaging said star-wheel, a detent elastically connected to said pawl, means for varying the moment of inertia of said detent, and a series of teeth on the controller in position to be engaged by said detent.
23. In combination, an electric controller, a star-wheel mounted on said controller, a spring-actuated pawl engaging said star-wheel, a detent elastically connected to said pawl, means for varying the tension of said elastic connection, and a series of teeth on the controller in position to be engaged by said detent.
24. In combination, an electric controller, a star-wheel mounted on said controller, a spring-actuated pawl engaging said star-wheel, a detent, operating by reason of its moment of inertia, elastically connected to said pawl, means for controlling the operation of said elastic connection, and a series of teeth on the controller in position to be engaged by said detent.
25. In combination, an electric controller, a star-wheel mounted on said controller, a spring-actuated pawl engaging said star-wheel, a detent, operating by reason of its moment of inertia, elastically connected to said pawl, a dash-pot for controlling the operation of said elastic connection, and a series of teeth on the controller in position to be engaged by said detent.
26. In combination a controller having a series of operative positions or steps, means for permitting a rapid unobstructed movement of the controller between steps and a locking device for arresting such rapid movement during the resting periods of such steps.
27. In a motor-controller, an elastically-mounted detent for arresting movement of the controller, and means for changing the moment of inertia of said detent to regulate the speed of controlling the motor.
28. In a motor-controller, an elastically-mounted detent in operative relation to the controller and brought into engagement therewith by its inertia upon rapid operation of the controller, and means for impelling said detent toward a clutching device on the controller when the latter is operated at an excessive speed.
29. In a motor-controller, an elastically-mounted inertia-controlled detent adapted to arrest the controller on rapid application of power to the motor, and means for imparting a reciprocatory movement to the detent, whereby momentum will be imparted to it upon rapid application of power.
30. In a motor-controller, an elastically-mounted detent in operative relation to the controller and brought into engagement therewith by its inertia upon rapid operation of the controller, means for impelling said detent toward a clutching device on the controller when the latter is operated at an excessive speed, and means for retarding the backward movement of the detent with relation to the controller.
31. In a motor-controller, an elastically-mounted detent in operative relation to the controller and brought into engagement therewith by its inertia, means for impelling said detent toward a clutching device on the controller when the latter is operated at an excessive speed, and a dash-pot for retarding the backward movement of the detent with relation to the controller.
32. In a motor-controller, an elastically-mounted detent in operative relation to the controller and brought into engagement therewith by its inertia upon rapid operation of the controller, means for impelling said detent toward a clutching device on the controller when the latter is operated at an excessive speed, and an adjustable dash-pot for retarding the backward movement of the detent relatively to the controller, whereby the time limit of its engagement may be controlled.
33. In a motor-controller, a series of undulating teeth connected to the movable member thereof, a yielding pawl bearing on said teeth, a movable detent operated by said pawl, and a series of teeth in operative relation to said detent and adapted to be engaged thereby when the detent is moved by rapid operation of the controller.
34. In a motor-controller, a star-wheel, a pawl riding over said wheel, an elastically-mounted locking-detent controlled by said pawl and in operative relation to a ratchet-wheel in fixed relation to the controller and adapted to lock the controller by its inertia, and a dash-pot governing the rearward movement of said detent.
35. In a motor-controller, a star-wheel, a pawl riding over said wheel, an elastically-mounted locking-detent controlled by said pawl and in operative relation to a ratchet-wheel in fixed relation to the controller and

adapted to lock the controller by its inertia, and a dash-pot for governing the rearward movement of said detent, provided with a valve permitting the free admission of air

5 during the forward impulse of the detent.

36. In a motor-controller, a star-wheel rotated thereby, an elastically-mounted pawl riding over the indentations of said wheel, a locking-detent elastically connected with

10 said pawl, and a ratchet-wheel adapted to be

engaged by said detent under the force of inertia when the controller is too rapidly operated.

In witness whereof I have hereunto set my hand this 31st day of July, 1899.
